JOHN MATTHEWS, JR., OF NEW YORK, N. Y.

Letters Patent No. 96,823, dated November 16, 1869.

IMPROVEMENT IN SODA-WATER DRAUGHT-APPARATUS.

The Schedule referred to in these Letters Patent and making part of the same.

To all whom it may concern:

Be it known that I, JOHN MATTHEWS, Jr., of the city, county, and State of New York, have invented a new and improved Soda-Water and Sirup-Cooling and Draught-Apparatus, of which the following is a full, clear, and exact description, reference being had to the accompanying drawing, forming part of this specification, and in which—

Figure 1 represents a plan of an apparatus, made in duplicate, or with two fronts or faces, and corresponding details, constructed in accordance with my improvement;

Figure 2, a vertical section of the same, taken mainly through the centre of the apparatus, from front to front; and

Figure 3, a transverse view of the draught-cock or disk, fitted within the same, above the outlet to the nozzle thereof, in illustration of the passages, which serve to divide the stream issuing through or from the nozzle.

Similar letters of reference indicate corresponding parts.

This apparatus has the same leading characteristics as that which is the subject of my Letters Patent, dated October 3, 1865.

The improvements consist, first, in a tumbler-guide, arranged to guide and adjust the tumblers to their places, for the reception of the sirup; and, secondly, in certain provision to prevent leakage from the sirup-tank stall, around the nozzles of the sirup-tanks, and permit the escape, to a suitable receptacle, of any liquid that may collect within the said stall.

Referring to the accompanying drawing—

A represents the sides, and B, the top or lid of the stand or case, which is supposed to be made of marble, said stand being here shown constructed as for a double apparatus, but the invention at large and in detail applies equally to a single one.

This case is divided by a sheet-metal casing or lining, S, or casings or linings, into compartments C D E C' D'.

The compartments C C' serve, by suitable divisions a, to receive or accommodate the different sirup-tanks E, while the compartments D D' answer to receive the tumblers, when it is required to charge them with sirup, or, it may be, to store the tumblers, these last-named compartments being provided with doors or shutters b, controlled by weighted levers c, that, accordingly as they are adjusted up or down, keep the compartments D D' open or closed.

On or along the bottom of these compartments D D', either in a loose or fixed manner, and resting, it may be, upon the counter on which the apparatus stands, is or are the tumbler-guides F, made, preferably, of wire, so as to form V or other equivalently-shaped compartments d, corresponding to the number of sirup-

tanks, and arranged, so that on entering from the front the several tumblers within the compartments D D', they will be automatically guided by the sides of the compartments d to their places, centrally, or thereabout, under the several sirup-tank outlets.

The sirup-tanks E are, preferably, constructed of glass, with an offset, e, disposed to admit of the discharge of the sirup at or through their bottoms, near their fronts, while they have an enlarged capacity for sirup in rear of their outlets, they being, more or less, of a parallelogramic form, with filling and valve-stem openings f g at top.

The advanced position of the offset e serves to establish a forward discharge for the sirup, which renders a deep or far-back insertion of the tumblers unnecessary, yet gives a roomy capacity to the tanks, and is altogether a novel construction of sirup-tank.

Said sirup-tanks are each provided with a valve-seat and valve, the valve-seat G being a separate and distinct device, made hollow, and of glass, with holes h i above and below, or through it, the one hole i being shaped to form a discharge-nozzle, and the body of the seat being ribbed or corrugated, to form, when cemented to its place, a secure fit in the offset e of the tank.

The valve H, which controls the discharge of sirup from the tank, may be of double-disk form, to open or close either opening h i, accordingly as the stem k of said valve is lifted or allowed to drop, the descent of the valve shutting off the discharge of sirup into the tumbler beneath, while the lift of it establishes the supply thereto in any suitable or measured quantity, which the two disks of the valve, controlling the openings h i, readily admit of, and the weight of the knob or handle on the upper end of the stem serving, on being released, effectually and rapidly to close the discharge from the tank.

By making the valve-seat G of glass, the condition of the valve, or cause of any obstruction to it, may be readily seen or ascertained without unscrewing or separating the parts.

The casing S, or such portion of it as forms the compartments C C', subdivided into stalls by partitions a, is bent or turned up at its edges, x, where perforated, to receive through it the nozzles of the sirup-tanks or valve-seats thereto, and such bent or turned-up edges covered with a rubber buffer, I, which, thus applied or arranged, as seen in fig. 2, will not only serve to break the shock in dropping the sirup-tanks to their places, and so prevent breakage, but also answer to guide the tanks, by their nozzles or valve-seat outlets, to their proper relative position.

Another object in turning up the edge x, or it may be otherwise forming a raised border round the perforation through which the tank or valve-seat nozzle

fits, is to prevent the passage of liquid arising from condensation, or sirup that may have leaked, from escaping through said perforation into the compartment D or D', and so on to the counter; and in order to better provide against this, even in case of breakage of any of the tanks, I establish an opening, z, at or near the bottom of either tank-stall in communication with the compartment E, and arranged below the level of the raised edge or border x, to carry off the escape into the compartment E.

The lid or cover B of the apparatus, which may be loose, and made whole, or in section s hinged together, as desired, is held and adjusted to its place on or over the sides A by metallic pins l, made to fit or enter holes m formed in metallic corner-braces J, that thus serve alike to hold together or brace the sides A of the case, and to form pockets or guides for the pins l.

By this construction, too, metal is brought to bear against metal in shutting to the lid, thereby avoiding chipping or splitting of the marble by the pins or dowels l, and excluding dirt from disfiguring the marble, besides adding to the strength of the structure.

The side or sides A of the stand or case opposite the chamber E is glazed, or made transparent, preferably by duplicate panes n n', arranged at a suitable distance apart, so as to form an air-space at the side or sides of the chamber E, which confined air, acting as a non-conductor, restrains the melting of the ice in said chamber.

By providing the stand or case with a transparent side or sides, too, the working of the water through the coolers is exhibited from the outside, also the quantity or condition of the ice surrounding the coolers in the compartment E, which avoids unnecessary opening of the lid.

The soda or mineral-water outlet-pipe (or, where more than one, pipes,) K terminates, as usual, at its outer extremity, in a draught-cock, L, which here, however, is of peculiar construction. Thus the nozzle w of said cock, I make of glass, and thereby prevent that chemical action and injury which take place when drawing off mineral-water, and which mark or stain the extremity of a metal nozzle; also form said cock with a peculiar arrangement of passages in the swell or portion above the nozzle, so that on the cock being opened, the water will be allowed to escape into the nozzle w, in a direct and rapid manner, through a small or contracted orifice, r, which is concentric, or thereabout, to the outlet through the nozzle, while the balance of the stream passing through the cock is

broken, or its velocity impeded, and the same spread or divided, by, in its entry to the nozzle, being diverted and caused to pass over a bridge, s, and through slots or segmental passages u, outside of the orifice r.

This arrangement insures a rapid small central run of the stream, which, striking or being injected over the sirup in the tumbler, effectually accomplishes its mixture, while it so breaks or retards and diffuses the main supply of aerated water, that is externally or outside of the mixing-portion of the stream, as to prevent objectionable and excessive agitation or effervescence within the tumbler.

A convenient mode of thus constructing the passages r u, with intervening bridge s over the nozzle-outlet, is to employ a separate disk, N, so constructed, and to fit the same within a screw-cap or collar, O, that serves to unite the nozzle w to the cock.

P is the usual wood bottom, which is used, in connection with the marble stand or case, to carry or sustain the interior metallic casing. This bottom is usually fastened to the marble of the outer case, by screws passing therethrough, which affords no provision for that contraction and expansion of the wood that invariably take place from time to time, and strain upon the marble, so as to endanger the breakage of the latter.

To obviate this, I fit the bottom P in loose, by slipping over its ends metallic hollow braces Q, and unite these latter, by screws r, with the outer case, thus leaving the wood bottom P free to shrink or expand, and yet causing it to sustain the interior casing in all positions, including even reversal of it, the same giving a better or firmer hold on the wood than is attainable by screws merely entering its ends.

What is here claimed, and desired to be secured by Letters Patent, is—

1. A tumbler-guide, F, constructed and applied or arranged for use, substantially as specified.

2. The turned-up edge or border x, around the openings provided in the bottom of the sirup-tank stall, for the reception of the tank-nozzles and the elastic envelope I, and the opening or openings z, at or near the bottom of the tank-stall, all arranged substantially as herein set forth, for the purpose of preventing leakage around the tank-nozzles, and permitting the escape of any liquid collecting in the stall.

JOHN MATTHEWS, JR.
